LOCOMOTIVE STOKER

Ernest B. Marsden, Erie, Pa., assignor to The Standard Stoker Company, Incorporated, a corporation of Delaware

Application August 7, 1947, Serial No. 767,034

5 Claims. (Cl. 198—15)

1

My invention relates to a flexible and sectional fuel conveying conduit system and particularly to a stoker conduit system mounted in and extending from beneath the fuel bin of a tender to the firebox of a locomotive.

In the ordinary operation of a locomotive and tender, relative longitudinal movement occurs between the two vehicles as they travel around curves, and as slack therebetween is taken up in starting and stopping. It is, therefore, essential that the stoker conduit system of a stoker for delivering fuel from the tender bin to the locomotive firebox, be so constructed and mounted as to allow for such relative movement.

Numerous ways have been previously suggested for accomplishing this end, notably by mounting the trough conduit of the stoker on the tender underframe to slide or roll longitudinally with respect thereto, or by providing a telescopic arrangement of the intermediate conduit connecting the rigidly mounted tender unit of the stoker and the rigidly mounted locomotive unit of the stoker.

An object of the present invention is to provide a novel and practical flexible and telescopic stoker conduit system and its arrangement with a locomotive and tender that will afford the necessary longitudinal extensibility and contractibility of the stoker conduit system as relative longitudinal movement between the locomotive and tender occurs.

Another object of the invention is to provide a novel and practical telescopic stoker tender unit and mounting thereof on the locomotive tender, the major portion of the tender unit of the stoker being rigidly mounted on the tender.

Another object of the invention is to provide in a stoker conduit system wherein the forward end thereof is rigidly mounted on the locomotive and the rearward end thereof is rigidly mounted on the tender, a novel and practical construction and arrangement of parts affording the necessary extensibility and contractibility to compensate for relative longitudinal movement between an intercoupled locomotive and tender.

Further objects and advantages will become apparent as the following description is read in connection with the accompanying drawings, in which

Figure 1 is a vertical longitudinal section through adjacent ends of a locomotive and tender taken at one side of the longitudinal center line thereof, with the novel stoker conduit system applied thereto, and shown in elevation with parts broken away and shown in section;

2

Figure 2 is a sectional view taken on the line 2—2 of Figure 1; and

Figure 3 is a sectional view taken on the line 3—3 of Figure 1.

5 An intercoupled locomotive and tender is shown in Figure 1, the locomotive being designated by the letter L, the tender by T, and the coupling connection therebetween by C. The coupling C, which may be of any well known construction, permits articulation between the locomotive and tender, and provides for the usual amount of relative longitudinal movement between them.

10 A stoker indicated generally by the letter S, conveys fuel from beneath the fuel bin 10 of the tender to the firebox 11 of the locomotive. The stoker S includes a conduit system comprising a trough conduit section 12 mounted on the tender, a discharge conduit section 13 rigidly mounted on the locomotive, and an intermediate conduit section 14 connecting the conduit sections 12 and 13. A flexibly connected sectional screw conveyor 15 advances the fuel through the conduit sections 12, 13 and 14.

15 The trough section 12 includes a relatively short U-shaped front trough portion 16 and a relatively long U-shaped rear trough portion 17 which are telescopically connected, as herein-after described, to provide for relative longitudinal movement therebetween.

20 The rear trough portion 17 is preferably of built-up construction including the rear cast trough member 18 having a preferably integrally cast gear housing 19; and a bent U-shaped sheet metal trough member 20 received in and secured in any suitable manner to the cast trough member 18. It is apparent, however, that the rear trough portion 17 may be formed as an integral unitary casting, or built up in any suitable manner, if desired. The rear trough portion 17 is rigidly secured to the tender floor 21, but may, if desired, be rigidly secured through suitable support members to the tender underframe 22.

25 The means for rigidly securing the rear trough portion 17 on the tender, shown in the drawing, includes a pair of angle bars 23 and 24, secured to the underside of the floor 21 by suitable means, as by the bolts 25. The angle bars 23 and 24 extend longitudinally along the opposite side marginal edges of the floor 21 defining the longitudinally elongated rectangular opening 26 therein. The opening 26 permits fuel to drop by gravity from the bin 10 into the trough section 12, whence it is conveyed forwardly to the locomotive firebox 11 by the sectional screw conveyor 15.

The rearward end of the front trough portion 16 fits closely about the forward end of the rear trough portion 17, and is in telescopic engagement therewith. The upper edges of the side walls 27 and 28 of the front trough portion 16 are provided, respectively, with the laterally outwardly extending horizontal flanges 29 and 30 arranged to be received by the longitudinally extending brackets 31 and 32, respectively. The brackets 31 and 32 are rigidly secured, in any suitable manner, to the under side of the floor 21, and are so formed to provide guideways permitting the front trough portion 16 to slide longitudinally with respect to the rear trough portion 17. The front trough portion is thus pendentially and longitudinally slidably supported from the tender floor 21 and affords the necessary extensibility and contractibility of the stoker conduit system as relative longitudinal movement between the locomotive and tender occurs.

A hollow spherical shell 33, provided with a short tubular portion 34 which registers with the opening 35 in the front wall 26 of the front trough portion 16, is rigidly secured to the front trough portion 16 in any suitable manner. The hollow spherical shell 33 is arranged to be received in the vertically split spherical clamp 37 of the intermediate conduit section 14, forming a universal joint connection between the intermediate conduit section 14 and the trough section 12.

The lower end of the discharge conduit section 13 is formed with a horizontally split spherical seat 38, receiving the ball member 39 of the intermediate conduit section 14, to form a universal joint connection between the two conduit sections. The universal joint connections in the conduit system allow for relative angular movement between the conduit sections as relative angular movement between the locomotive and tender occurs in traveling over curving track.

It will be observed that, in the stoker construction above described, the entire trough 12, including the rigid rear trough portion 17 and the longitudinally slidably front trough portion 16, is open at its top to receive fuel from the bin 19. The front of the trough is readily accessible for removal of rail spikes, tramp iron and other foreign material should they be caught between the screw flight and the marginal edge of the front wall of the trough defining the discharge outlet 35.

From the foregoing, it is apparent that while the trough conduit section of the stoker is arranged to compensate for relative longitudinal movement between the locomotive and tender, the major portion of the trough is adapted to be rigidly mounted on the tender. Only a small forward portion of the trough is pulled forward or pushed rearward on the tender by the locomotive as relative longitudinal movement between the two vehicles occurs, thereby minimizing the strain imposed on the front sections of the conduit system and on parts of the locomotive as compared to constructions in which the entire trough section is pulled forward or pushed rearward in the tender by the locomotive. At the same time the conduit system dispenses with relatively longitudinally moving parts between the forward end of the trough and the discharge conduit, and the entire trough is open to the fuel bin to receive fuel therefrom.

I claim:

1. A stoker for an intercoupled locomotive and tender, including a fuel discharge conduit sec-

tion adapted to be rigidly mounted on the locomotive, a fuel receiving conduit comprising a rearward open mouth forwardly opening trough member adapted to be rigidly mounted on the tender and a forward open mouth rearwardly opening trough member telescopically related and in axial alignment with said rearward trough member to provide for relative longitudinal movement between said trough members, means for pendentially supporting said forward trough member from the tender deck, and an inextensible intermediate conduit flexibly connected at its ends with said discharge conduit and said forward open mouth trough member.

2. A stoker for an intercoupled locomotive and tender, including a fuel discharge conduit section adapted to be rigidly mounted on the locomotive, a fuel receiving conduit comprising a rearward open mouth forwardly opening trough member adapted to be rigidly secured to and supported from the tender deck and a forward open mouth rearwardly opening trough member telescopically related and in axial alignment with said rearward trough member to provide for relative longitudinal movement between said trough members, means for pendentially supporting said forward trough member from the tender deck, and an inextensible intermediate conduit flexibly connected at its ends with said discharge conduit and said forward open mouth trough member.

3. A stoker for an intercoupled locomotive and tender, including a fuel discharge conduit section adapted to be rigidly mounted on the locomotive, a fuel receiving conduit comprising a rearward open mouth forwardly opening trough member adapted to be rigidly mounted on the tender and a forward open mouth rearwardly opening trough member telescopically related and in axial alignment with said rearward trough member to provide for relative longitudinal movement between said trough members, means for pendentially supporting said forward trough member from the tender deck, said means arranged to arrest any but relative longitudinal movement of said forward trough member with respect to said tender deck, and an inextensible intermediate conduit flexibly connected at its ends with said discharge conduit and said forward open mouth trough member.

4. A fuel receiving tender trough unit of a stoker adapted to be mounted beneath the tender deck, comprising a rearward open mouth forwardly opening trough member adapted to be rigidly mounted on the tender and a forward open mouth rearwardly opening trough member mounted telescopically and in axial alignment with the forward end of said rearward trough member to provide for relative longitudinal movement between said trough members, the overlapping surfaces of said telescoping members fitting closely one within the other, a pair of laterally spaced longitudinally extending guide supports adapted to be rigidly secured to the underside of the tender deck, and flanges formed with and extending laterally from the upper ends of the side walls of said forward trough member arranged to be received in said guide supports for pendentially supporting said forward trough member, said guide supports and flanges co-operating to arrest any but longitudinal movement of said forward trough member with respect to said rearward trough member.

5. In a locomotive tender having a fuel bin provided with a floor having a longitudinally

elongated fuel discharge opening, a sectional trough mounted to receive fuel by gravity from said bin through said opening, said trough comprising a forwardly opening rearward trough member rigidly mounted on the tender, a rearwardly opening forward trough member in overlapping telescopic relation and in axial alignment with said rearward trough member to provide for relative longitudinal movement between said trough members, a longitudinally extending guide support rigidly secured to the underside of said floor at each side of the forward portion of said discharge opening, and a flange formed with and projecting laterally from the upper edge of each side of said forward trough member, said flanges being received in said guide supports for

pendently supporting said forward trough member, said guide supports and flanges cooperating to arrest any but longitudinal movement of said forward trough member with respect to said rearward trough member.
